HUSH TUBE

Morris J. Hyman, Philadelphia, Pa.

Application September 9, 1938, Serial No. 229,047

1 Claim. (Cl. 285—55)

My invention relates to hush pipes as used in water closets and relates particularly to replacing broken-off hush pipes.

Water closets have a stream of water enter into a chamber, and the release of a control wall valve permits the water to be discharged into the waste bowl. The water entering into the chamber passes through a control valve which is usually at the upper part of the chamber, and the opening or closing of the valve is controlled by a float whereby the valve is closed when the float reaches the upper predetermined level. The incoming water passes through the valve and exhausts through an elongated hush tube which extends from the valve at the upper part of the chamber to the lower part of the chamber. The purpose of having the elongated pipe is to enable the water to descend from the upper part of the chamber to the lower part of the chamber with a silencing action.

The hush tube is generally composed of copper and is screw-threaded into a complementary opening in the valve. In the course of time, corrosion occurs at the junction of the valve and the hush tube, and the corrosion causes the hush pipe to break from the valve. If the hush pipe is not replaced, the water will descend from the top of the chamber through the valve and drop noisily upon the bottom of the chamber.

To remove the valve and rethread the valve to receive a new hush tube is not only a laborious task but is difficult; because if the hush tube has broken, there is also a likelihood that the other parts of the valve are corroded.

Heretofore, no devices have been constructed to replace the hush tube without removing the valve.

It is, therefore, an object of my invention to provide a replacement for a corroded broken-off hush tube.

A further object of my invention is to provide a self-threading hush tube which can be easily inserted in the broken-off piece of pipe.

Other objects of my invention are to provide an improved device of the character described, that is easily and economically produced, which is sturdy in construction and which is highly efficient in operation.

With the above and related objects in view, my invention consists in the following details of construction and combination of parts, as will be more fully understood from the following description, when read in conjunction with the accompanying drawing, in which:

Fig. 1 is a fragmentary view of a water-closet water retainer and the water inlet and valve.

Fig. 2 is a fragmentary sectional view of a self-threading replacement hush tube.

Fig. 3 is a fragmentary sectional view of a modification of an easily insertable replacement hush tube.

Fig. 4 is a fragmentary sectional view of still another modification of my invention.

Referring now in greater detail to the drawing, I show in Fig. 1 a water closet, generally designated as A, having a chamber 10 within which is a control valve, generally designated as B, of the customary construction having a float 12. The discharge tube 14 of the control valve B (Fig. 2) usually has a screw thread 16 therein to receive an end of a screw-threaded hollow pipe, and when the pipe corrodes and is broken off, a small section 18 of pipe remains in the valve discharge outlet 14. Since the water closet chamber 10 is relatively narrow and the defining wall is high, it is almost impossible to remove the remaining broken piece of pipe in order to insert a newly threaded hush tube.

I, therefore, case harden a tapered threaded bushing C having facets 20 thereon and force a piece of metal tubing D into the bore of the bushing. The facets serve as surfaces whereby a wrench may be used to tighten the bushing. I then turn the self-threading bushing C into the broken-off piece of tube 18 so that the end 22 of the hush tube is adjacent the bottom of the chamber.

To provide an additional silencing action to the hush tube D, I may add a plurality of grooves 35 to the lower end of the tube whereby the whirling water will trickle softly from the tube.

In Fig. 3 I show a second modification of my invention wherein a hush tube D1 has one end expanded to provide a flange 30, and the tube's diameter near the flange is reduced, as at 32, to receive the bore of the case hardened self-threading bushing C1. The bushing C1 is held tightly between the flange 30 and an inturned portion 34 of tube D1, and the bushing's bore tightly receives the outer diameter of the reduced portion 32 of the tube. The major portion of the tube is of a diameter equal to that of the replaced tube in order to permit water to properly pass therethrough.

In Fig. 4 I show a third modification of my invention wherein a hush tube D2, preferably composed of copper, has an out-turned end flange 40. Spaced from the flanged end of the tube is a threaded portion 42 upon which a threading cou-

pling 44 interfits. Between the coupling's upper edge 46 and the lower edge of the end flange 40 and surrounding the outer portion of the hush tube D2 is a rubber ring 48. When the rubber ring 48 is in its uncompressed state, it fits into the bore of the broken-off pipe 18; and in that position, the rubber ring can be expanded by compressing the edges of the ring inwardly when the nut 44 is turned. In such manner, a new hush tube can be inserted into the valve while it is in the water closet.

Although my invention has been described in considerable detail, such description is intended as illustrative rather than limiting, since the in-

vention may be variously embodied, and the scope of the invention is to be determined as claimed.

I claim as my invention:

A hush tube adapted to be joined to a broken piece of pipe in a discharge outlet comprising a tube, a portion of said tube adjacent one end having an inturned flange, the outer end of the tube outwardly turned to form a second flange, a self-threading bushing positioned between the in-turned and out-turned flanges, and said thread 10 being adapted to be connected into a broken-off piece of metallic pipe. 5
